UNITED STATES PATENT OFFICE.

WILLIAM KNEEN, OF BARROW-IN-FURNESS, COUNTY OF LANCASTER,
ENGLAND.

MEANS FOR CONSUMING SMOKE.

SPECIFICATION forming part of Letters Patent No. 340,918, dated April 27, 1886.

Application filed February 2, 1886. Serial No. 190,573. (No model.) Patented in England June 17, 1885, No. 7,393.

To all whom it may concern:

Be it known that I, WILLIAM KNEEN, builder, a subject of the Queen of Great Britain and Ireland, and residing at 66 Scott Street, 5 Barrow-in-Furness, in the county of Lancaster, England, have invented certain new and useful Improvements in Means for Consuming Smoke and Economizing Fuel in Steam-Boilers, (for which I have applied for a patent in 10 Great Britain, No. 7,393, on the 17th June, 1885,) of which the following is a specification.

My invention has for its principal object to consume the smoke or combustible products 15 from furnaces or fires which would otherwise escape. I thus effect economy in fuel.

According to my invention, I provide in the rearward part of the furnace or furnaces, or so as to be heated by the flames therefrom, contracted spaces or chambers constituting zigzag passages or baffling-surfaces. The flue or 20 flues from the furnace or furnaces conduct the smoke and unconsumed products of combustion on their way to the chimney into these contracted spaces or chambers, by which they 25 are divided into numerous small streams, which are caused to impinge against the baffling-surfaces provided therein. Air is supplied by a fan or otherwise to the gases as 30 they pass into each of the contracted passages, and as the surfaces in the said contracted passages are in a highly-heated condition the gaseous mixture is ignited as it impinges against the baffling-surfaces, which causes a 35 generation of great additional heat, thereby greatly augmenting the heating-power of the furnace or fire relatively to the amount of fuel consumed and preventing or greatly reducing nuisance from escaping smoke. The 40 flames resulting from the ignition of the gaseous mixture may be conducted by a return-flue, so as to utilize the heat therefrom.

The invention may be applied to the consumption of smoke from coke-ovens or other 45 places where smoke is generated; and in order that my said invention may be fully understood I shall now proceed more particularly to describe a manner of performing the same, and for that purpose shall refer to the 50 several figures on the annexed sheet of drawings, the same letters of reference indicating corresponding parts in all the figures.

The accompanying drawings represent a portion of a steam-boiler sufficient to explain the said application of my invention.

Figure 1 is a vertical section; Fig. 2, a horizontal sectional plan, and Fig. 3 a transverse vertical section at the rear of the bridge.

In the flue at the rear of the bridge I build a chamber, A, of fire-clay or other suitable 55 material, having on it a number of zigzag passages, a, through which the products of combustion from the furnace B pass. In front of the structure A are conduits, pipes, or passages C, which open into an air-chamber, D, 60 into which air is led by a pipe, E. Into these pipes, conduits, or passages air from a blower or air-forcing apparatus is forced, the said air becoming heated in its passage, and issuing in a number of jets or in a divided state from 65 the orifices c into the passages a, where it and the products of combustion commingle and are baffled by the various surfaces against which they impinge, and the air causes effective burning of the said products and the generation of great additional heat.

It will be understood that the invention can be employed generally for the consumption of smoke and economy of fuel in furnaces and fires, and that smoke or products of combustion from any source can, according to my invention, be passed through zigzag heated passages or against equivalent baffling-surfaces and be mixed with air in fine streams or jets for the generation from the said products of 85 heat that would otherwise be wasted.

Having now particularly described and ascertained the nature of my said invention and in what manner the same is to be performed, I declare that what I claim is—

The combination of a fire-place or furnace with heated zigzag passages in communication therewith and means for passing air in a finely-divided state into said zigzag passages, substantially as and for the purpose set forth.

In testimony whereof I have signed my name to this specification in the presence of two subscribing witnesses.

WILLIAM KNEEN.

Witnesses:
